DRAIN VALVE DEVICE

Clyde C. Farmer, Pittsburgh, Pa., assignor to The Westinghouse Air Brake Company, Wilmerding, Pa., a corporation of Pennsylvania

Application January 18, 1936, Serial No. 59,716

14 Claims. (Cl. 303—1)

This invention relates to means adapted for use on the main reservoir of a fluid pressure brake system to drain the moisture which accumulates in the reservoir.

5 Many types of drain valve devices have heretofore been developed to drain the moisture from the reservoirs employed in fluid pressure brake systems, but these devices have not been entirely satisfactory because in freezing weather the 10 water in the reservoir and in the passage leading to the drain valve device may freeze and thereby render the drain valve device inoperative.

The drain valve devices which have heretofore 15 been provided have not included any means to melt ice after it has formed, or to open the passage to the drain valve device when it is closed by ice, and it has been necessary, therefore, to supply heat from an external source to melt this 20 ice so that the drain valve device might be rendered operative.

It is the principal object of this invention to 25 provide means to thaw ice which forms in the passage leading to the drain valve device for a fluid pressure reservoir.

A further object of the invention is to provide 30 means to thaw ice which forms in the passage leading to the drain valve device for a fluid pressure reservoir, which means does not require the use of an external source of heat.

Another object of the invention is to provide 35 means to thaw ice which forms in the passage leading to the drain valve device for a fluid pressure reservoir and which employs the heat of the fluid under pressure contained in the reservoir.

Other objects of the invention and features of 40 novelty will be apparent from the following description taken in connection with the accompanying drawing, in which,

45 Fig. 1 is a view, largely in section, of a reservoir equipped with the thawing means provided by my invention, and

Fig. 2 is a sectional view showing a valve employed in the means shown in Fig. 1, the valve 50 being shown in a different position than that in which it is shown in Fig. 1.

Referring to the drawing there is shown a reservoir 1, which may be the main reservoir of a fluid pressure brake system. This reservoir may 55 be of any suitable construction and is supplied with fluid under pressure from a compressor, not shown, by way of a pipe 3, while fluid under pressure is withdrawn from the reservoir by way of a pipe 5.

55 The reservoir 1 has associated therewith an

automatic drain valve device, indicated generally by the reference numeral 7, which operates automatically in response to variations in the pressure in a portion of the brake system to open a passage through which water accumulated in the 5 reservoir may be discharged.

The drain valve device 7 may be of any well known construction and one form of device which I may employ is shown in my U. S. Patent No. 1,801,853, issued April 21, 1931.

The drain valve device 7 is connected with the lower portion of the reservoir 1 by way of a curved pipe 10 which is threaded into a reinforcing member 12, which is secured to the reservoir 1 surrounding an opening therein.

The pipe 10 extends into the reservoir 1 a short distance and has passages or openings 14 cut through the wall thereof which communicate with the interior of the reservoir at points adjacent the bottom thereof.

The arm of the pipe 10 to which the drain valve device 7 is connected is somewhat longer than the arm of the pipe which is connected to the reservoir so that the drain valve device 7 is located substantially above the bottom of the reservoir 1, while the upper wall of the pipe 10 at the lowest portion of the pipe is located vertically below the bottom of the reservoir 1, and also vertically below the automatic drain valve device 7.

A pet cock 16 is secured in an opening in the pipe 10 a short distance below the drain valve device 7 so as to communicate with the interior of the pipe 10 at a point vertically below the automatic drain valve device 7, and vertically above the lowest portion of the reservoir 1 and above the upper wall of the pipe 10 at the lowest portion of this pipe.

The pet cock 16 has a passage 18 extending therethrough and communication through this 40 passage is controlled by means of a plug valve 20 which is operated by a handle 22.

The pipe 10 may be covered with a layer of suitable heat insulating material indicated at 24, which serves to retard the flow of heat between 45 the pipe and the atmosphere.

A pipe or conduit 26 of substantially smaller diameter than the pipe 10 is provided. The pipe or conduit 26 communicates with the interior of the reservoir 1 at a point adjacent the upper wall 50 thereof and extends through the closed end wall of the pipe 10. The pipe or conduit 26 is bent so as to have substantially the same curvature as the pipe 10, and is positioned substantially centrally of the pipe 10 so as to be spaced from the 55

inner wall of the pipe 10 and to provide a passage for the flow of water through the pipe 10 outwardly of the pipe 26.

The pipe 26 extends to a point in the pipe 10 5 a short distance below the drain valve device 7 and has a restricted opening 28 formed in the end thereof. It will be seen that the pipe 26 communicates with the pipe 10 at a point adjacent the automatic drain valve device 7, and that this 10 point is located vertically below the automatic drain valve device 7, but is also located vertically above the point at which the pipe 10 communicates with the reservoir 1 and also vertically above the upper wall of the pipe 10 at the lowest portion 15 thereof.

In operation the plug valve 20 of the pet cock 16 is normally turned to the position in which it is shown in Fig. 1 of the drawing, in which position it cuts off communication through the passage 18.

20 Water which collects in the reservoir 1 as a result of operation of the brake equipment flows by gravity to the lower portion of the reservoir and flows therefrom through the openings 14 to the pipe 10, and it accumulates in the lower portion of 25 the pipe 10 which is located substantially below the lowest portion of the reservoir 1.

The level of the water in the pipe 10 will rise until the level in both arms of the pipe 10 has increased substantially to the level of the upper 30 wall of the pipe 10 at the lowest portion thereof. On the further flow of water from the reservoir to the pipe 10 the level of the water in the arm of the pipe 10 which communicates with the reservoir 1 will increase, but the level of the water in 35 the other arm of the pipe 10 will not increase as the rise in the level of the water in this arm is prevented by the air which is trapped in the pipe 10 beneath the automatic drain valve device 7.

On the occurrence of the condition to which the 40 drain valve device 7 is adapted to respond this device operates to open the communication which it controls, and there results a reduction in the pressure of the fluid in the portion of the pipe 10 below the drain valve device 7. The pressure of 45 the air in the reservoir 1 acting upon the water which has accumulated in the pipe 10 and also in the lower portion of the reservoir 1, thereupon forces this water through the pipe 10 and out through the communication opened by the automatic drain valve device 7.

When the drain valve device 7 operates to open the communication controlled thereby, air from the reservoir flows through the pipe or conduit 26 and through the restricted opening 28 out through 55 the drain valve device 7. The rate of flow of air through the restricted communication 28 is so small, however, that this flow of air does not affect the discharge of water through the automatic drain valve device 7.

60 After a brief time interval the drain valve device 7 operates to close the communication controlled thereby, and thus cuts off the release of water and of air from the reservoir 1 by way of the pipes 10 and 26.

65 If the reservoir 1 is exposed to temperatures below freezing for a substantial period of time the water which accumulates in the lower portion of the pipe 10 and in the reservoir 1 may freeze. If this occurs then on subsequent operation of the 70 automatic drain valve device 7 to open the communication controlled thereby the ice in the pipe 10 will prevent the water in the reservoir 1 from being expelled through the passage opened by the automatic drain valve device 7 and water will 75 continue to accumulate in the reservoir 1.

The means provided by this invention makes it possible to melt ice which forms in the pipe 10 without the use of external heat and thereby render the automatic drain valve device 7 operative to vent water from the reservoir 1.

5 In the event that ice forms in the pipe 10 it may be melted by turning the plug valve 20 of the pet cock 16 to the position to establish communication through the passage 18, which is the position in which it is shown in Fig. 2 of the drawing.

10 When the passage 18 through the pet cock 16 is opened air from the upper portion of the reservoir 1 is permitted to flow from the reservoir through the conduit 26 and through the restricted opening 28 to the portion of the pipe 10 adjacent 15 the automatic drain valve device 7 and therefrom to the atmosphere by way of the passage 18 through the pet cock 16.

20 During the operation of the fluid pressure brake system air under pressure is supplied to the reservoir 1 by the air compressors, not shown, and this air is normally at a temperature substantially above the freezing temperature of water. When this air flows through the conduit 26 it heats the walls of this conduit and this heat is transmitted 25 through the walls of the conduit to the ice which has formed in the pipe 10 in the passage between the conduit 26 and the pipe 10.

30 This causes the ice in the pipe 10 to be melted and thereby establishes a passage through the pipe 10 through which air from the reservoir 1 may flow to the automatic drain valve device 7, so that when the automatic drain valve device 7 is operated to open the passage controlled thereby, air from the reservoir 1 may flow through the pipe 10 and expel the water which has accumulated in the pipe 10. In addition, the relatively warm air from the reservoir 1 which flows through the pipe 10 melts any ice which remains in the pipe 10 which is not melted by heat communicated 40 thereto from the conduit 26.

35 After a time interval the plug valve 20 of the pet cock 16 is turned to the position in which it is shown in Fig. 1 of the drawing so as to cut off communication through the passage 18 and 45 thereby restore the apparatus to the normal operating condition.

40 If the water in the pipe 10 should freeze again it may again be thawed by repeating the operation.

50 It will be seen that the apparatus provided by this invention provides means to thaw ice which forms in the passage leading to an automatic drain valve device and that this means operates without the use of an external source of heat.

55 While one embodiment of the invention has been illustrated and described in detail, it should be understood that the invention is not limited to these details of construction, and that numerous changes and modifications may be made without departing from the scope of the following claims.

60 Having now described my invention, what I claim as new and desire to secure by Letters Patent, is:

65 1. In combination, a reservoir adapted to contain fluid under pressure, a drain pipe through which liquid collecting in said reservoir may be discharged from the reservoir, a conduit disposed within said pipe and connected to a source of 70 heated fluid under pressure, and means for establishing a flow of heated fluid under pressure from said source through said conduit to thereby melt ice which may be formed by the freezing of liquid within said pipe.

2. In combination, a reservoir into which fluid is compressed by a compressor, a drain pipe through which liquid collecting in said reservoir may be drained off, a conduit disposed within said pipe and connected to receive fluid under pressure from said reservoir which is heated through the compressive action of the compressor, and means for establishing a flow of said heated fluid under pressure through said conduit.

10 3. In combination, a reservoir adapted to contain air under pressure, a passage through which liquid may be discharged from said reservoir, valve means controlling communication through said passage, the passage having a portion intermediate the reservoir and the valve means located vertically below the valve means and vertically above the point of connection of the passage with the reservoir, a conduit contained in said passage, said conduit communicating with the reservoir at a point vertically above the point of connection of the passage with the reservoir and extending from the reservoir to a point in said passage vertically above the point of connection between the passage and the reservoir, and means to establish a flow of air from the reservoir through said conduit.

4. In combination, a reservoir adapted to contain air under pressure, a passage through which liquid may be discharged from said reservoir, valve means controlling communication through said passage, the passage having a portion located vertically below the point of connection of the passage with the reservoir and vertically below the valve means, a conduit contained in said passage, said conduit communicating with the reservoir at a point vertically above the point of connection of the passage with the reservoir and extending from the reservoir to a point in said passage vertically above the upper wall of the passage at the lowest point in the passage intermediate the valve means and the reservoir, and means to establish a flow of air from the reservoir through said conduit.

5. In combination, a reservoir adapted to contain air under pressure, a passage through which liquid may be discharged from said reservoir, valve means controlling communication through said passage, the passage having a portion intermediate the reservoir and the valve means located vertically below the valve means, a conduit contained in said passage, said conduit communicating with the reservoir at a point vertically above the point of connection of the passage with the reservoir and extending from the reservoir to a point in said passage vertically above the upper wall of the passage at the lowest point of the said passage, and means to establish a flow of air from the reservoir through said conduit.

6. In combination, a reservoir adapted to contain air under pressure, a passage through which liquid may be discharged from said reservoir, said passage communicating with the reservoir at a point adjacent the lowest portion thereof, valve means controlling communication between the atmosphere and the passage at a point on the passage vertically above the point at which the passage communicates with the reservoir, the passage having a portion intermediate the reservoir and the valve means located vertically below the point at which the passage communicates with the reservoir, a conduit contained in said passage, said conduit communicating with the reservoir at a point vertically above the point at which the passage communicates with the reservoir and extending from the reservoir to a point

in the passage adjacent the valve means, and means for establishing a flow of air from the reservoir through said conduit.

7. In combination, a reservoir adapted to contain air under pressure, a passage through which liquid may be discharged from said reservoir, said passage communicating with the reservoir at a point adjacent the lowest portion thereof, valve means controlling communication between the atmosphere and the passage at a point on the passage vertically above the point at which the passage communicates with the reservoir, the passage having a portion intermediate the reservoir and the valve means located vertically below the point at which the passage communicates with the reservoir, a conduit contained in said passage, said conduit communicating with the reservoir at a point vertically above the point at which the passage communicates with the reservoir and extending from the reservoir to a point in the passage adjacent the valve means and vertically above the point of connection of the passage with the reservoir, and means for establishing a flow of air from the reservoir through said conduit.

8. In combination, a reservoir adapted to contain air under pressure, a passage through which liquid may be discharged from said reservoir, said passage communicating with the reservoir at a point adjacent the lowest portion thereof, valve means controlling communication between the atmosphere and the passage at a point on the passage vertically above the point at which the passage communicates with the reservoir, the passage having a portion intermediate the reservoir and the valve means located vertically below the point at which the passage communicates with the reservoir, a conduit contained in said passage, said conduit communicating with the reservoir at a point vertically above the point at which the passage communicates with the reservoir and extending from the reservoir to a point in the passage adjacent the valve means and vertically above the upper wall of the passage at the lowest point thereof, and means for establishing a flow of air from the reservoir through said conduit.

9. In combination, a reservoir adapted to contain air under pressure, a passage through which liquid may be discharged from said reservoir, valve means controlling communication through said passage, the passage having a portion intermediate the reservoir and the valve means located vertically below the valve means, and a conduit contained in said passage, said conduit communicating with the reservoir at a point vertically above the point of connection of the passage with the reservoir, said conduit extending from the reservoir to a point in the passage adjacent the valve means and communicating with the passage at a point vertically above the upper wall of the passage at the lowest point thereof.

10. In combination, a reservoir adapted to contain air under pressure, a passage through which liquid may be discharged from said reservoir, valve means controlling communication through said passage, the passage having a portion intermediate the reservoir and the valve means located vertically below the valve means, a conduit contained in said passage, said conduit communicating with the reservoir at a point vertically above the point of connection of the passage with the reservoir, said conduit extending from the reservoir to a point in the passage adjacent the valve means and communicating with the pas-

sage at a point vertically above the upper wall of the passage at the lowest point thereof, and means for establishing communication between said passage and the atmosphere at a point on the 5 passage intermediate the upper wall of the passage at the lowest point thereof and the valve means.

11. In combination, a reservoir adapted to contain air under pressure, a passage through which 10 liquid may be discharged from said reservoir, valve means controlling communication through said passage, the passage having a portion intermediate the reservoir and the valve means, a conduit 15 contained in said passage, said conduit communicating with the reservoir at a point vertically above the point of connection of the passage with the reservoir, said conduit extending from the reservoir to a point in the passage adjacent the 20 valve means and communicating with the passage at a point vertically above the upper wall of the passage at the lowest point thereof, and manually controlled means for establishing communication 25 between said passage and the atmosphere at a point on the passage intermediate the upper wall of the passage at the lowest point thereof and the valve means.

12. In combination, a reservoir adapted to contain air under pressure, a passage through which 30 liquid may be discharged from the reservoir, said passage communicating with the reservoir at a point adjacent the lowest portion thereof, valve means controlling communication between the passage and the atmosphere at a point on the 35 passage vertically above the point at which the passage communicates with the reservoir, the passage having a portion intermediate the reservoir and the valve means located vertically below the point of connection of the passage with the reservoir, a conduit contained in said passage and 40 communicating with the reservoir at a point vertically above the point at which the passage communicates with the reservoir, said conduit extending from the reservoir to a point in the passage on the side of the lowest point in the passage adjacent the valve means and communicating 45 with the passage at a point vertically above the point of connection of the passage and the reservoir, and means to establish communication

between the passage and the atmosphere at a point on the passage adjacent the valve means and located vertically above the point of connection of the passage with the reservoir.

13. In combination, a reservoir adapted to contain air under pressure, a passage through which liquid may be discharged from the reservoir, said passage communicating with the reservoir at a point adjacent the lowest portion thereof, valve means controlling communication between the 10 passage and the atmosphere at a point on the passage vertically above the point at which the passage communicates with the reservoir, the passage having a portion intermediate the reservoir and the valve means located vertically below the 15 point of connection of the passage with the reservoir, a conduit contained in said passage and communicating with the reservoir at a point vertically above the point at which the passage communicates with the reservoir, said conduit extending from the reservoir to a point in the passage on the side of the lowest point in the passage adjacent the valve means and communicating 20 with the passage at a point vertically above the point of connection of the passage and the reservoir, and manually controlled means to establish communication between the passage and the atmosphere at a point on the passage adjacent the valve means and located vertically above the point of connection of the passage with the 25 reservoir.

14. In combination, a reservoir adapted to contain air under pressure, a passage through which liquid may be discharged from the reservoir, valve means controlling communication through said passage, the passage having a portion intermediate the reservoir and the valve means located vertically below the valve means, a conduit having a portion of the wall thereof exposed to liquid in said passage, the conduit communicating with the reservoir at a point vertically above the point of connection of the passage with the reservoir and extending from the reservoir to a point in the passage adjacent the valve means and located vertically above the point of connection of the 40 passage with the reservoir, and manually controlled means for establishing a flow of air from the reservoir through said conduit.
